UNITED STATES PATENT OFFICE.

JOHN H. COX, OF HOT SPRINGS, ARKANSAS.

TIE AND RAIL-HOLDER.

1,127,595.

Specification of Letters Patent.

Patented Feb. 9, 1915.

Application filed April 21, 1914. Serial No. 833,487.

To all whom it may concern:

Be it known that I, JOHN H. COX, a citizen of the United States, residing at Hot Springs, in the county of Garland and State 5 of Arkansas, have invented certain new and useful Improvements in Ties and Rail-Holders, of which the following is a specification.

This invention relates to an improved tie 10 which is intended to be used in railroad construction, and the principal object of the invention is to provide a tie formed of rolled steel which will have its end portions so constructed that they will be resilient, thus 15 forming yieldable supports for the railroad rails.

Another object of the invention is to provide improved means for connecting the rails with the ties, the connecting means being so constructed that the distance between 20 the rails may be varied by adjustment of the connecting means.

This invention is illustrated in the accompanying drawings wherein—

25 Figure 1 is a top plan view of the tie with the rails in place; Fig. 2 is a view showing a tie and rails in elevation; Fig. 3 is a side elevation showing a pair of rail sections connected with the improved tie; 30 Fig. 4 is a bottom plan view of one end portion of the tie; Fig. 5 is a transverse sectional view taken along the line 5—5 of Fig. 4.

The tie 10 is formed of rolled steel, and 35 has its central portion cut away as shown at 11 so that the weight of the tie will be reduced. The end portions of the tie are sawed to provide longitudinally-extending slots 12 dividing the end portions of the tie 40 into the base portions 13 and rail chairs 14. The rail chairs 14 are each provided with bolt-receiving openings 15 positioned in alignment with rectangular openings 16 formed in the base sections 13 to receive the 45 heads 17 of the bolts 18.

The rails are secured to the rail chairs 14 by means of the fasteners 20 and 21 which 50 resemble fish plates and are provided with feet 22 and 23 through which the bolts 18 pass. The feet 22 are longer than the feet 23 and therefore by reversing the positions of the fish plates 20 and 21, the rails 19 may be adjusted longitudinally upon the tie, as indicated at the right of Fig. 1. In order 55 to separate the ties from the rails, pads

24 are placed beneath the ties, as shown in Fig. 2.

When constructing a track, the ties are laid upon the road-bed, and the bolts are then passed through the aligned openings 15 and 16. The rails are then put in place, and the fish plates placed against the rails with the bolts passing through the feet 22 and 23. The locking nuts are then secured upon the bolts and hold the fish plates tightly in 65 place. If it is desired to widen the track at a curve, the fish plates 20 and 21 will be interchanged, thus moving either one or both of the rails to the position shown in dotted lines in Fig. 1. As the train moves over the 70 track, the rail chairs 14 can give, and thus the pounding of a train will be taken up by the resiliency of the rail chairs; and the ties will thus be protected from excessive pounding.

75 I have thus provided a rolled steel tie which will be very strong and durable and not liable to become bent or broken from pounding, and which is provided with improved rail-securing means so constructed 80 that the rails may be adjusted longitudinally upon the tie, and thus the distance between the rails varied.

What is claimed is:

1. A tie formed of rolled resilient material having its end portions provided with longitudinally-extending slits forming resilient rail chairs positioned in spaced relation to the lower portion of the ends of the tie, each of said rail chairs being provided with fastener-receiving openings formed in alignment with openings formed in the lower portion of the tie, the lower openings being shaped to engage the lower portions of the fasteners passed through the aligned openings and prevent rotation of the fasteners.

2. A tie having its end portions provided with resilient rail chairs positioned in spaced relation to the lower portions of the ends of the tie, said rail chairs being provided with fastener-receiving openings formed in alignment with openings formed in the lower portions of the ends of the tie, the last-mentioned openings being cut to engage the lower portions of fasteners passed through the aligned openings to prevent rotation of the fasteners.

3. A tie having its end portions provided with rail chairs positioned in spaced rela-

tion above the end portions of the tie and terminating short of the ends of the tie provided with fastener-receiving openings positioned in alignment with locking openings formed in the lower portions of the end portions of the tie, the lower openings being cut to engage the lower portions of the fasteners and lock the fastener against rotation.

- 10 4. A tie formed of resilient material having its end portions cut to form rail chairs positioned in spaced relation above the end portions of said tie, said rail chairs being provided with fastener-receiving openings 15 positioned in alignment with the openings formed in the end portions of said tie, inner and outer fish plates provided with feet having openings formed therein to reg-

ister with the openings of said rail chairs, the feet of one fish plate of each set being 20 of greater length than the feet of the other fish plate to permit adjustment of the rails longitudinally upon the tie, and fasteners passing through the aligned openings and having their lower end portions provided 25 with heads fitting into the openings formed in the end portions of the tie and conforming to the shape of said openings to prevent rotation of said fasteners.

In testimony whereof I affix my signature in presence of two witnesses.

JOHN H. COX.
